S. P. JOHNSON,
GRENADE THROWER OR GUN,
APPLICATION FILED OCT. 18, 1920.

1,412,017.

Patented Apr. 4, 1922.

UNITED STATES PATENT OFFICE.

STUART P. JOHNSON, OF WASHINGTON, DISTRICT OF COLUMBIA, ASSIGNOR TO
NEWTON D. BAKER, SECRETARY OF WAR, TRUSTEE.

GRENADE THROWER OR GUN.

1,412,017.

Specification of Letters Patent.

Patented Apr. 4, 1922.

Application filed October 18, 1920. Serial No. 417,800.

(FILED UNDER THE ACT OF MARCH 3, 1883, 22 STAT. L., 625.)

To all whom it may concern:

Be it known that I, STUART P. JOHNSON, a citizen of the United States, and a resident of Washington, District of Columbia, have 5 invented an Improvement in Grenade Throwers or Guns, of which the following is a specification.

The invention described herein may be used by the Government, or any of its officers or employees in prosecution of work for the Government, or by any other person in the United States, without payment of any royalty thereon, in accordance with the Act of March 3, 1883.

15 The subject of this invention is an ordnance device intended, primarily, as a grenade thrower or gun.

In designing a device of this character it is desirable that the ordinary service cartridge may be used therein for the reason that the distribution of various kinds of ammunition to troops would lead to many mistakes and delays and place an unnecessary burden on the troops and on those supplying them with ammunition.

20 Since some grenades projected from a grenade thrower or gun, such as a pyrotechnic grenade, have very thin casings or bodies it is essential that means be provided 30 to prevent the bullet of an ordinary service cartridge from penetrating or injuring the shell of the grenade.

It is further desirable that the grenade used in a grenade thrower or gun be a solid 35 one with no center passage therethrough for the escape of the bullet so that the full effect of the gases in explosion may be centered upon the grenade to propel the same from the gun.

40 In designing a gun of this character it is an advantage if the same can be so designed as to utilize parts of old, worn-out rifles or guns.

For the purpose of securing accuracy of 45 fire it is necessary that a grenade gun be designed to be fired from the shoulder of the user rather than by the old method of placing the butt of the gun upon the ground or against some other fixed and substantial 50 support.

For the purpose of securing the hereinbefore mentioned advantages and overcoming the heretofore mentioned objections the

present invention consists generally in a grenade gun provided with a shock absorber in the stock thereof and a barrel designed for attachment in place of the barrel of an ordinary rifle and provided with a cartridge chamber so constructed as to relieve the pressure of the gases of explosion 60 upon the bullet and so retard the flight of the bullet as to prevent the same from injuring or penetrating the grenade thrower or casing.

Specifically the invention consists in a 65 barrel capable of attachment in place of the barrel of an ordinary rifle and having a cartridge chamber from one-sixteenth to one-eighth inch longer than the cartridge shell and formed to permit the neck of the 70 shell to expand under the pressure of the gases of explosion and to shear from the shell body at the base of the bullet.

With these and other objects in view the invention consists in a novel arrangement 75 and combination of parts and in the details of construction hereinafter described and claimed, it being understood that changes in the precise embodiments of the device herein disclosed may be made within the 80 scope of what is claimed without departing from the spirit of the invention.

A practical embodiment of the invention is shown in the accompanying drawing, 85 wherein—

Fig. 1 is a view in side elevation, partly in section, of a grenade thrower constructed in accordance with the invention;

Fig. 2 is an enlarged fragmentary view 90 in longitudinal section showing the cartridge chamber and a portion of the barrel with a cartridge in place in the chamber and a grenade in position in the barrel;

Fig. 3 is a view in elevation showing 95 the condition of the shell after firing.

Referring to the drawings by numerals of reference: The lock or center portion of an ordinary rifle is shown carried by a stock 1 and provided with a bolt 2 carrying the firing pin 3 which is released by the trigger 4. This portion of the rifle is provided with the usual block 5 which is apertured and threaded as at 6 for the reception of the rifle barrel.

The portion of the device involved in the 100 present invention consists of a barrel 7, of

enlarged diameter, capable of receiving the ordinary grenade, the rear end of which barrel is interiorly threaded to receive the breech closure block 8, which block is centrally apertured and threaded for the reception of the member 9, the extending rear end of which is threaded to engage with the threads 6 on the block 5 and so assemble the barrel with the lock mechanism. If desired, the barrel 7 may be secured in place by means of the locking screw 10 which is threaded through the forward portion of the stock, the barrel 7, and breech closure block 8 into member 9.

The member 9 is centrally apertured to provide a cartridge chamber 11, the forward portion of which is of reduced bore forming an annular shoulder 12 adapted to engage the cartridge shell at the point at which said shell begins to taper from the neck. The reduced portion 13 of the bore is of a diameter sufficient to receive loosely the neck of the cartridge so as to permit the same to expand freely under pressure of the gases of explosion while the annular shoulder 12 prevents the cartridge from being thrust forward beyond the desired distance. As shown the forward portion of the member 9 in which is formed the reduced bore 13 extends forwardly of the breech closure block 8 and into the rear of the bore of the barrel 7. This forwardly extending portion is provided with a series of radially extending apertures 14 which communicate with the bore 13 and with the bore of the barrel 7 and which are so situated as to be located in a plane at right angles to the axis of the bore and passing adjacent the rear of the bullet of the ordinary service cartridge.

From a consideration of Fig. 2 it will be seen that the cartridge shell 15 fits snugly in the chamber 11 and contacts the annular shoulder 12, with the neck 16 of the cartridge projecting into the reduced bore 13 and the bullet 17 extending, for the major portion of its length, into the bore of the barrel 7 and forming a stop against which the grenade 18 rests, thus assuring a uniform and constant spacing of the grenade from the base of the barrel.

In order that the device may be readily fired from the shoulder of the operator, the stock 1 is provided with a recess in its butt end adapted to receive a casing 19 which is tapped for the reception of the piston rod 20 and a pair of spring guides 21-21. Slidably mounted in the rear of the casing 19 is a casing 22 which is tapped to receive a cylinder 23 in which works a piston 24 mounted on the piston rod 20. Coiled springs 25-25 encircle the guides 21-21 with their forward ends abutting the head of the casing 19 and their rear ends abutting the head of the casing 22 for the purpose

of holding the casings in normally extended 65 position.

The operation of the device is as follows: The firing mechanism operates in the usual way, cartridges being automatically fed to the cartridge chamber and fired by actuation 70 of the trigger 4 to release the firing pin 3. Upon explosion of the powder in the cartridge shell 15, the neck 16 will be expanded to fill the bore 13 and the force of the gases of explosion will further shear the neck 16 75 through the apertures 14 and sever the neck from the main portion of the shell at the base of the bullet. Since the bullet is practically unconfined, extending as it does for the major portion of its length into the 80 bore of the barrel 7, the gases are free to escape around the bullet and exert thereon a very slight propelling force, so that the acceleration of the bullet is such as not to equal or more than equal the acceleration 85 of the grenade, the consequences being that the bullet is incapable of injuring the grenade and its flight is so reduced that it carries but a short distance and not with sufficient force to become a menace to the 90 troops in the vicinity of the operation of the gun.

Upon the recoil of the gun the piston 24 travels in the cylinder 23 compressing the air therein and taking up the shock of recoil. This shock is also partially absorbed by the springs 25-25 which, after being compressed, act to restore the parts to normal position.

Having described my invention what I 100 claim as new and desire to secure by Letters Patent is:

1. In a grenade gun, a cartridge chamber having a bore for the reception of the main portion of the cartridge shell and a reduced 105 bore for the reception of the neck of the cartridge shell, the diameter of the reduced bore being greater than the diameter of the neck of the cartridge shell and means communicating with the reduced bore whereby 110 the force of the gases of explosion will sever the neck of the cartridge shell from the main portion thereof.

2. In combination with a grenade gun provided with a cartridge chamber and a 115 barrel, a cartridge positioned in the chamber and a grenade positioned in the barrel and normally resting against the nose of the bullet of the cartridge.

3. In combination with a grenade gun 120 provided with a cartridge chamber and a barrel, a cartridge positioned in the chamber, a grenade positioned in the barrel and normally resting against the nose of the bullet of the cartridge and means for absorbing the shock of recoil of the gun. 125

STUART P. JOHNSON.
